UNITED STATES PATENT OFFICE.

PAUL INDERMUHLE, OF ROBBINSVILLE, NEW JERSEY.

BROODER.

1,175,766.

Specification of Letters Patent. Patented Mar. 14, 1916.

Application filed August 8, 1913. Serial No. 783,809.

To all whom it may concern:

Be it known that I, PAUL INDERMUHLE, a citizen of the United States, residing at Robbinsville, in the county of Mercer and State of New Jersey, have invented new and useful Improvements in Brooders, of which the following is a specification.

This invention relates to brooders and it consists in the novel features hereinafter described and claimed.

An object of the invention is to provide a brooder of simple structure adapted to be placed upon the surface of the ground and having a floor which is spaced above the ground. In the space between the floor and the surface of the ground is located a lamp or other suitable heating device for the brooder. The floor is provided with openings located in the vicinity of the walls of the brooder for permitting the heat from the lamp or other heating device to pass up into the upper portion of the brooder. A curtain is stretched transversely across the upper portion of the brooder and is slashed at its lower edge portion in order that the chicks may pass freely from one side of the curtain to the other side. The brooder is provided at its side with hinged doors having transparencies through which light may be admitted into the brooder and at one end the brooder is provided with an opening through which the chicks may pass as they leave or enter the brooder.

In the accompanying drawing:—Figure 1 is a perspective view of the brooder. Fig. 2 is a longitudinal sectional view of the same. Fig. 3 is a transverse sectional view of the same. Fig. 4 is a horizontal sectional view of the same.

The brooder comprises a body 1 having a sloping roof or top 2. The roof 2 may be permanently fixed to the body 1 or detachable therefrom as desired. The body 1 is provided at its ends and in the vicinity of the roof 2 with openings 3 through which foul air may pass out of the body 1. A floor 4 is supported in the body 1 above the lower edge thereof and the said floor is cut away at its corners as at 5 in order that heat may pass from below the floor above the same. A curtain 6 depends from the roof 2 and the lower edge portion of the curtain is slashed whereby the curtain is rendered sufficiently flexible to permit the chicks to pass freely from one side to the other and at the same time the curtain will

prevent strong drafts of air passing through the brooder or along the floor. The body 1 is provided at one end with opening 7 and an inclined foot-piece 8 over which the chicks may pass as they enter and leave the body. The body 1 is provided at its side with hinged doors 9 which are located at the opposite sides of the curtain 6 hereinbefore described. These doors 9 are provided with transparencies 10 through which light may be admitted into the brooder. Any suitable securing devices as for instance buttons 11 may be provided upon the body 1 for holding the doors 9 in closed position. 70 A shield 12 preferably of sheet metal is supported from the under side of the floor 4 by means of brackets 13 which are attached to the floor and the corner portions of the said shield. Brackets 13 hold the shield 12 75 spaced from the floor. A lamp 14 is adapted to rest upon the surface of the ground below the floor and the said lamp is preferably provided with a glass chimney 15, glass being used for the reason that it 80 does not accumulate soot nor will it rust. The body 1 is provided at its side and at a point below the floor 4 with openings 16 through which air may pass from the interior into the said body. Below the floor 85 this air is heated by the lamp and moves up into the upper portion of the brooder to the openings provided at the cutaway portions 5 of the floor 4 and then up and out of the body 1 through the opening 3. 90 The shield 12 prevents the heat from the lamp 14 from coming in direct contact with the floor immediately above the lamp and consequently there is no danger of the brooder becoming heated by the lamp to 95 such an extent as to start fire. In practice a hole is dug in the ground and the lamp 4 is positioned in the same. The body 1 is then placed over the lamp so that the shield 12 is spaced approximately one inch from 100 the upper end of the chimney 15. Therefore it will be seen that the body 1 is closed at its lower edge by the surface of the ground and the floor 4 is sufficiently heated to render the same comfortable to the chicks. 105 The chicks may roost upon the floor and they may be fed thereon at either or both sides of the curtain 6.

Having described the invention what is claimed is:—

A brooder comprising a body open at its lower side, a roof closing the upper side of

the body, a floor located in the body between the roof and its lower open side, said floor being cut away at its corner portions and immediately at the corners of the body, thereby providing openings at the corner portions of the body, said body being provided at its side and below the floor with openings and a heat spreader located below the floor and spaced from the same and hav-

ing its edges spaced from and terminating 10 short of the openings at the corners of the body.

In testimony whereof I affix my signature in presence of two witnesses.

PAUL INDERMUHLE.
